REFRIGERATION APPARATUS

Elliott E. Grover, Springfield, Mass., assignor to
Westinghouse Electric & Manufacturing Company,
East Pittsburgh, Pa., a corporation of
Pennsylvania

Application January 10, 1939, Serial No. 250,192

8 Claims. (CL 62—1)

This invention relates to refrigeration apparatus and more particularly to a means for mounting the refrigerant condensing unit in a refrigerator cabinet.

One object of the invention is to provide a mounting for a refrigerant condensing unit which minimizes the vibration and noises transmitted from the refrigerator unit to the refrigerator cabinet and to the room in which the unit is operated.

Another object of the invention is to provide a resilient mounting for a refrigerant condensing unit in a refrigerator cabinet which provides sufficient support for the unit to afford shipping the assembled refrigerator without any additional securing of the refrigerating unit in the refrigerator cabinet.

These and other objects are effected by my invention as will be apparent from the following description and claims taken in connection with the accompanying drawings forming a part of this application, in which:

Fig. 1 is a side elevation of a mechanical refrigerator embodying the invention with the side walls of the machine compartment of the refrigerator broken away;

Fig. 2 is a rear elevation of the refrigerator of Fig. 1 with the lower portion of the air duct and some of the tubing broken away to show the refrigerating unit;

Fig. 3 is a detail elevation of the refrigerant condensing mechanism and the resilient supports of the mechanism with parts of the mechanism broken away;

Fig. 4 is an enlarged side elevation of the upper rubber support for the refrigerant condensing unit;

Fig. 5 is an end elevation of the support of Fig. 4;

Fig. 6 is an enlarged side elevation of one of the lower supports for the refrigerant condensing unit; and,

Fig. 7 is an end elevation of the support shown in Fig. 6.

Referring now specifically to the drawings for a detail description of the invention, the reference numeral 10 designates a refrigerator cabinet having a food storage compartment 11 in the upper portion and a machine compartment 12 in the lower portion. The machine compartment 12 is cooled by an air duct having its entrance in the opening 13 in the rear wall of the refrigerator cabinet 10. The air passes underneath a baffle 15 and upwardly through the machine compartment 12 and outwardly through a rear opening 55

16 of the machine compartment 12 and upwardly through an air duct 17. This arrangement of air ducts aids in silencing the noise of a refrigerant condensing unit 18 located in the machine compartment 12.

The refrigerant condensing unit 18 comprises a sealed casing 19 housing a reciprocating compressor 21 and a motor 22 for driving the same through a horizontal drive shaft 20. The casing 19 contains lubricating oil (not shown) at a level slightly below the rotor of the motor 22. The portion of the casing 19 housing the motor 22 is provided with U-shaped cooling fins 23. A refrigerant condenser 24 is secured to the fins 23 by means of a shroud 25. A fan 26 driven by a motor 27 provides for drawing air through the condenser 24 and passing this air through the U-shaped fins 23.

The various refrigerant ducts are as follows: 20 A suction tube 28 carries the refrigerant vapor from an evaporator (not shown) in the food storage compartment 11 to the interior of the casing 19. A tube 29 carries the compressed refrigerant from the pump 21 in the casing 19 to the condenser 24, and a capillary impedance tube 31 carries the liquefied refrigerant to the evaporator. The tubes 28, 29 and 31 are coiled adjacent the condensing unit 18 to provide for resiliency. As thus far described, the apparatus is 30 old and in all the essential details is similar to the apparatus shown in Patent No. 2,080,595 issued to W. B. Anderson et al. and assigned to the assignee of the present application.

The condensing unit 18 is supported at the rear 35 of the machine compartment 12 by two resilient supports 32. The supports 32 are shown in Figs. 6 and 7 and comprise a horizontal rubber cylinder 33 vulcanized at one of its ends to a metal disc 34 having a central screw threaded nipple 35 and at its other end to an upper portion of a bracket 37. The bracket 37 has a base 38 formed into a cradle to limit the movement of the rubber cylinder 33 when severe shocks are encountered during shipment. To form the cradle, the base 38 has end portions bent upwardly at an angle. The rear supports 32 of the condensing unit 18 are secured by screws 39 to a metal cross channel 41 in the lower, rear portion of the machine compartment 12. The casing 19 of the 50 motor and compressor is provided with a formed steel bracket 42 on each side. These brackets 42 are secured to the discs 34 of the supports 32 by screws 43.

The other side of the condensing unit 18 is secured at its upper end to a somewhat similar

resilient support 44. This support 44 is shown in detail in Figs. 4 and 5 and comprises a horizontal rubber cylinder 45 vulcanized at each end to discs 46 provided with screw threaded studs 47. The upper portion of the condenser 24 is provided with a yoke 48 secured to the sides of the condenser 24. One stud 47 of the support is passed through a hole in the central upper portion of the yoke 48 and is held in place by a washer 49 and a nut 51. The other stud 47 of the support 44 is secured in a similar manner to the central web 52 of a channel member 53 secured at its upper and lower ends 54 to structural cross members 55 in the machine compartment 12. It will be observed that the rubber cylinders 33 and 45 are stressed in shear and sag under the weight of the condensing unit 18 as shown in Figs. 1 and 3. The weight distribution of the condensing unit 18 is such that the center of mass represented by Z in Figs. 2 and 3 lies near but slightly above a plane X, Y passed through the center of the movable ends of the rubber cylinders 33 and 45. In determining this center of mass, the lubricating oil normally in the unit was removed and the coil of the tubes 29 and 31 adjacent the unit 18 was cut at its midpoint. The weight distribution of the condensing unit 18 is furthermore such that each of the supports 32 and 44 are substantially equally loaded.

The particular position of the resilient supports 32 and 44 described produces unusually quiet operation of the condensing unit. The rubber in the supports provides a relatively resilient cushioning during slight deflections of the unit 18 such as occur during normal operation. The resiliency of the rubber decreases rapidly, however, when the limit of its deflectability is approached as may occur when the refrigerator is jarred during shipment. This decreased resiliency near the limits of the deflectability of the rubber prevents the refrigerant condensing unit from striking against the cabinet wall during shipment and makes the use of hold-down bolts or blocking unnecessary. This invention also avoids the necessity of opening the machine compartment at the customer's premises to remove the hold-down screws or blocking, which heretofore required considerable time and was sometimes forgotten, necessitating a service call.

From the above it will be apparent that this invention provides a mounting for a refrigerant condensing unit which minimizes the vibrations and noises transmitted from the condensing unit to the refrigerator cabinet and to the room in which the unit is operated and further provides a mounting providing protection against jolts which ordinarily would slam the unit against the walls of the cabinet.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. In a mechanical refrigerator, the combination of a cabinet, a unitary structure comprising a refrigerant pump at one end thereof, a motor adjacent said pump for driving the same, a condenser on the other side of said motor, and a casing for said pump and motor, said condenser being substantially at the same level with said cas-

ing, and means for mounting said unitary structure in said cabinet comprising a plurality of supports having resilient elements near the lower portion of the pump end of said casing and a further resilient element near the upper portion of said condenser.

2. In a mechanical refrigerator, the combination of a cabinet, a unitary structure comprising a refrigerant pump, a motor adjacent said pump, a condenser at one end of said unitary structure, a casing for said pump and motor, a fan, and a motor for driving the same, said fan and its driving motor being located between the condenser and the casing and said condenser being substantially at the same level with said casing, and means for mounting said unitary structure in said cabinet comprising a support having a plurality of resilient elements near the lower portion of the end of said casing opposite the condenser and a further resilient element near the upper portion of said condenser.

3. Apparatus according to claim 2 in which the plurality of resilient elements near the lower portion of the motor end and the resilient element near the upper portion of the condenser are each loaded substantially equally.

4. In a mechanical refrigerator, the combination of a cabinet, a unitary structure comprising a compressor, a motor for driving the compressor, and a casing for enclosing said motor and compressor, a condenser disposed at one end of said casing, a fan, and a motor for driving the fan, said fan and its driving motor being located between the condenser and the casing, and means for mounting said unitary structure in said cabinet comprising resilient supporting means disposed near the lower portion of said casing opposite the condenser and further resilient supporting means disposed near the upper portion of said condenser.

5. In a mechanical refrigerator, the combination of a cabinet, a unitary structure disposed within the cabinet and comprising a compressor, a motor for driving the compressor and a casing for enclosing said motor and compressor, a condenser disposed substantially in horizontal alignment with the casing, means for attaching the condenser to the casing and means for mounting said unitary structure in said cabinet comprising resilient supporting means disposed near the lower portion of the end of the casing opposite from the condenser and further resilient supporting means disposed near the upper portion of said condenser.

6. Apparatus according to claim 5 in which the resilient supports comprise rubber-like material mounted to stress said material in shear.

7. In a mechanical refrigerator, the combination of a cabinet, a unitary structure comprising a reciprocating refrigerating pump at one end thereof, a motor adjacent said pump, a condenser at the other end of said unitary structure, a casing for said pump and motor, a fan, and a motor for driving the same, said fan and its driving motor being located between the condenser and the casing, and means for mounting said unitary structure in said cabinet comprising a plurality of rubber supports near the lower portion of the compressor end of said casing and a further rubber support near the upper portion of the condenser.

8. In a mechanical refrigerator, the combination of a cabinet, a unitary structure comprising

a reciprocating refrigerating pump at one end thereof, a motor adjacent said pump, a condenser at the other end of said unitary structure, a casing for said pump and motor, and means for mounting said unitary structure in said cabinet comprising a plurality of resilient elements near

the lower portion of the compressor end of said casing and a further resilient element near the upper portion of the condenser, said resilient elements lying in a plane passing close to the center of mass of said unitary structure.

ELLIOTT E. GROVER.
